FEEDING MECHANISM FOR SEWING MACHINES

Arthur N. Hale, Stratford, Conn., assignor to The Singer Manufacturing Company, Elizabeth, N. J., a corporation of New Jersey

Application December 28, 1948, Serial No. 67,704

12 Claims. (Cl. 112—215)

1

This invention relates to improvements in feeding mechanisms for sewing machines and has for its primary object to provide a high speed mechanism adapted to advance work efficiently across the free end of a sewing machine work-arm.

Another object of the present invention is to provide a compactly arranged smoothly operating feeding mechanism capable of being installed within the restricted space of a cylinder-bed sewing machine, which feeding mechanism is designed to maintain the work-engaging surface of the feed-dog substantially parallel to the work-plate throughout its work-advancing stroke.

The foregoing and other objects and advantages in view, together with means whereby the same may be carried into effect, will best be understood from the following description of a preferred embodiment thereof illustrated in the accompanying drawings, in which:

Fig. 1 is a front side elevation, partly in section, of a sewing machine embodying the present improvement.

Fig. 2 is an enlarged vertical section taken transversely of the work-arm substantially along the line 2—2, Fig. 1.

Fig. 3 is an enlarged perspective view of the work-arm end-plate showing the three pintles for supporting one end of the feed-lift and feed-advance rock-shafts.

Fig. 4 is an enlarged bottom plan view, partly in section, of the machine removed from its supporting base.

Fig. 5 is a vertical section taken substantially along the line 5—5, Fig. 4.

Fig. 6 is a perspective view, partly in section, of that portion of the feeding mechanism in the free end of the work-arm, illustrating the manner in which the feed-bar is connected to the feed-advance rock-shaft and the two feed-lift rock-shafts.

Fig. 7 is a disassembled perspective view of the angle link and its pivot-pins for connecting the feed-bar to the feed-advance rocker.

Fig. 8 is a vertical transverse section taken through the work-arm substantially along the line 8—8, Fig. 4.

Fig. 9 represents a diagrammatic view of that portion of the feeding mechanism located at the free end of the work-arm.

Referring to the drawings, the present invention has been embodied in a sewing machine supported upon a hollow base or pedestal 10 and having a frame comprising a bed 11 from which rises the standard 12 of a hollow bracket-arm 13

2

terminating in a head 14. The bracket-arm head 14 overhangs the free end of an elliptical work-arm 15 extending from the frame-bed 11.

Journaled for rotation in the bracket-arm 13 is a horizontally disposed main actuating shaft 16 carrying at one end a belt-driven balance-wheel 17 and at its other end operatively connected to a needle-bar 18. The needle-bar 18 is journaled for endwise reciprocation in the bracket-arm head 14 and carries at its lower end a threaded needle 19. Slidably mounted in the head 14 rearwardly of the needle-bar 18 is a spring-influenced presser-bar 20 carrying at its lower end a common form of hinged presser-foot 21.

Complemental to the needle 19 in the formation of lock-stitches is a loop-taker 22, preferably of the rotary hook type. The rotary hook 22 is fast upon the outer end of a hook-shaft 23 (Fig. 20) having secured on its inner end a pinion gear 24 meshing with an internal gear 25 carried on the end of a rotary bed-shaft 26. The bed-shaft 26 is journaled in bearings 27 and 28, and is driven by a suitable belt 29 from the arm-shaft 16.

Opposing the presser-foot 21 in advancing work past the stitch-forming devices is my improved feeding mechanism comprising a feed-dog 30 having a laterally extending shank 31 preferably fastened by screws 32 to a feed-bar 33. As shown in Figs. 1 and 2, the feed-bar 33 is positioned on the machine-standard side of the rotary hook 22 and is arched to provide two depending legs 34 and 35 which straddle the usual mounting hub 36 of the rotary hook, whereby a compact arrangement is provided which permits the parts to be made of sufficient size as to impart adequate rigidity to them. As will be seen in Figs. 2 and 6, the legs 34 and 35 of the feed-bar 33 are formed with slideways 37 and 38 in which are disposed slide-blocks 39 and 40 pivotally carried at the free ends of a pair of inwardly directed rock-arms 41 and 42 preferably integral with a pair of substantially parallel feed-lift rock-shafts 42 and 43 disposed lengthwise of the work-arm 15 on opposite sides of the hook-shaft 23. The feed-lift rock-shaft 43 is oscillated on its supporting pintles 44 and 45 by means of a rock-lever 46 (Figs. 4 and 8) whose lower end is connected by a pitman 47 to a feed-lift eccentric 48 secured upon the bed-shaft 26. To effect synchronous oscillation of both of the feed-lift rock-shafts 42 and 43, the rock-shaft 42, supported on pintles 49 and 50, is linked to the rock-shaft 43 preferably in the manner illustrated in Fig. 5. It will be seen in this figure that

the rock-shaft 43 has clamped on it a second rock-lever 51 connected by a link 52 to a rock-lever 53 clamped on the rock-shaft 42. The rock-lever 51 extends downwardly from its supporting rock-shaft 43 and the rock-lever 53 extends upwardly from its supporting rock-shaft 42 while the link 52 connecting the two rock-levers is inclined and extends through the horizontal plane containing the longitudinal axes of the feed-lift rock-shafts 42 and 43. With the feed-lift rock-shafts connected together in this manner, oscillation of the driving feed-lift rock-shaft 43 will impart to the driven feed-lift rock-shaft 42, oscillations in opposite directions from those of the driving rock-shaft 43. The main advantages gained by driving one of the feed-lift rock-shafts from the other feed-lift rock-shaft is that proper synchronism of oscillation of the feed-lift rock-shafts is conveniently attained, and only one feed-lift driving eccentric is required on the bed-shaft 26. As will be observed in Fig. 2, simultaneous rocking of the lift-arms 40 and 41 will, through the slide-blocks 38 and 39, raise and lower the feed-bar 33 in a manner such that the serrated surface of the feed-dog 30 will remain substantially parallel to the plane of the work-supporting surface of the bed 15.

Timed with the feed-dog lifting mechanism is a feed-dog advance and return mechanism. Referring principally to Figs. 2 and 6, it will be seen that the leg 34 of the feed-bar 33 has an extension 54 which projects downwardly and laterally, terminating at a point below the plane containing the longitudinal axes of the two feed-lift rock-shafts 42 and 43 and substantially directly beneath the feed-lift rock-shaft 42. Pivoted to the lower or free end of the feed-bar extension 54, by means of the pin 55, is one limb 56 of an angle-lever 57 having its other limb 58 pivoted on a pin 59 secured in the upstanding spaced rock-arms 60, 61 preferably integral with a feed-advance and -return rock-shaft 62. The feed-advance and -return rock-shaft 62 is supported for oscillation on pintles 63 and 64. As shown in Figs. 4 and 8, the rock-shaft 62 has clamped on it a rock-arm 65, the upper end of which is connected by a pitman 66 to an adjustable feed-advance and -return eccentric 67 fast upon the rotary bed-shaft 26. Rotation of the bed-shaft 26 will impart oscillations to the feed-advance rock-shaft 62, which oscillations effect an advance and return to the feed-dog 30 in proper time with the rise and fall of the lift mechanism, whereby the usual four motions are imparted to the feed-dog to effect advance of the work past the stitch-forming instrumentalities. The amplitude of the feed-advance stroke is controlled by adjustment of the eccentric 67, the constructive details of the eccentric being substantially identical with the disclosure in the U. S. Patent of W. Myers, No. 2,128,031, granted August 23, 1938.

As shown in Fig. 3, the pintles 45, 50 and 63 which support the outer ends of the feed-advance rock-shaft 62 and the two feed-lift rock-shafts 42 and 43 are all secured to an end-plate 68 adapted to be attached to the end of the work-arm 15. The end-plate 68 also has fastened to it a bridge-piece 69 which carries a rotation-restraining lug 70 for the usual bobbin-case of the rotary hook 22.

From the above description, it will be understood that I have devised an improved feeding mechanism particularly adaptable for cylinder-bed sewing machines by virtue of the fact that

the parts are compactly arranged and are relatively disposed as to be smooth running and devoid of binding. Additionally, the use of two feed-lift rock-shafts arranged at opposite sides of 5 and substantially at the level of the hook-shaft 23 (Fig. 2) provides for raising and lowering the feed-dog 30 so that its serrated work-engaging surface remains in substantial parallelism with the throat-plate of the machine. Also, the location of the feed-advance rocker 60 and the angle-lever 57 below the horizontal plane containing the axes of the feed-lift rock-shafts 42 and 43 contribute to the compactness of the mechanism. As will be seen in Fig. 2, the loop-taker 22 is substantially centrally located in the cylinder-bed 15 and the components of the feeding mechanism are disposed in compact relation about the loop-taker. The body of the feed-bar 33 is disposed between the loop-taker 22 and the 10 work-support 71, while its legs 34 and 35 depend and straddle the loop-taker. The feed-advance rocker 60, 61, with its angle-lever connection to the feed-bar extension 54 provide a feed-advance mechanism which is crowded into a small space 15 without sacrificing any flexibility or smoothness of operation of the mechanism.

Having thus set forth the nature of the invention, what I claim herein is:

1. A work-feeding mechanism for sewing machines having a work-support, comprising a feed-dog, a rotary actuating shaft journaled beneath said work-support, feed-dog advance and return mechanism including a rock-shaft operatively connected to said rotary shaft, and feed-dog lift mechanism including a pair of rock-shafts operatively connected to be driven by said rotary shaft.

2. A work-feeding mechanism for sewing machines having a work-support, comprising a feed-dog, a rotary actuating shaft, feed-dog advance and return mechanism including a rock-shaft operatively connected to said rotary shaft, feed-dog lift mechanism including a pair of feed-lift rock-shafts, operative connections between one of said feed-lift rock-shafts and said rotary actuating shaft, and connections for driving the other of said feed-lift rock-shafts from said first feed-lift rock-shaft.

3. A work-feeding mechanism for sewing machines, comprising a feed-dog, a rotary actuating shaft, a feed-advance and -return eccentric mounted on said rotary shaft, feed-advance and -return connections actuated by said eccentric, a feed-lift eccentric mounted on said rotary actuating shaft, and feed-lift connections operatively connected to said feed-lift eccentric and including a pair of rock-shafts connected to oscillate in opposite directions.

4. A work-feeding mechanism for sewing machines, comprising a feed-dog, an actuating shaft, feed-dog advance and return mechanism operatively connected to said actuating shaft, feed-dog lift mechanism including a pair of feed-lift rock-shafts, operative connections between one of said feed-lift rock-shafts and said actuating shaft, a rock-lever secured to each of said rock-shafts, and a link connecting said rock-levers together.

5. A work-feeding mechanism for sewing machines, comprising a feed-dog, an actuating shaft, feed-dog advance and return mechanism operatively connected to said actuating shaft, feed-dog lift mechanism including a pair of feed-lift rock-shafts, operative connections between one of said feed-lift rock-shafts and said actuating

shaft, a rock-lever secured to each of said rock-shafts, and a link connecting said rock-levers together, said link extending through the plane containing the longitudinal axes of said feed-lift rock-shafts.

6. A work-feeding mechanism for sewing machines, comprising a feed-dog, a feed-bar carrying said feed-dog and provided with a pair of legs, feed-lift mechanism operatively connected to the legs of said feed-bar, a feed-advance rock-shaft, an extension provided on one of the legs of said feed-bar, and means including a link for connecting said feed-advance rock-shaft to said extension.

7. A work-feeding mechanism for sewing machines having a work-support and a loop-taker beneath said work-support, comprising a feed-dog disposed to operate through said work-support, a feed-bar arched to provide a pair of legs straddling said loop-taker, feed-lift mechanism including a pair of feed-lift rock-shafts operatively connected one to each of said feed-bar legs, and feed-advance mechanism including a feed-advance rock-shaft, a feed-advance rock-lever and a link connecting said feed-advance rock-lever to one of the legs of said feed-bar.

8. A work-feeding mechanism for sewing machines having a work-support and a circularly moving loop-taker beneath said work-support, comprising a feed-dog disposed to operate through said work-support, a feed bar having a body-portion disposed between said loop-taker and work-support and terminating in a pair of legs arranged to straddle said loop-taker, feed-lift mechanism including a pair of feed-lift rock-shafts operatively connected to said legs at substantially the level of the axis of movement of said loop-taker, and feed-advance mechanism including a feed-advance rock-shaft, and connections between said feed-advance rock-shaft and one of said feed-bar legs, said last named connections being below the level of the axis of movement of said loop-taker.

9. A work-feeding mechanism for sewing machines having a work-support and a circularly moving loop-taker beneath said work-support, comprising a feed-dog disposed to operate through said work-support, a feed-bar having a body-portion disposed between said loop-taker and work-support and terminating in a pair of legs arranged to straddle said loop-taker, feed-lift mechanism including a pair of feed-lift rock-shafts, substantially horizontal rock-arms carried by said feed-lift rock-shafts and extending towards each other for operative connection with said feed-bar legs substantially at the level of the axis of movement of said loop-taker, feed-advance mechanism including a feed-advance rock-shaft located below the plane containing the longitudinal axes of said feed-lift rock-shafts, an upstanding rock-arm secured to

said feed-advance rock-shaft, and operative connections between said upstanding rock-arm and one of the legs of said feed-bar.

10. A work-feeding mechanism for sewing machines having a work-support and a loop-taker beneath said work-support, comprising a feed-dog disposed to operate through said work-support, a feed-bar arched to provide a pair of legs straddling said loop-taker, each of said legs having a slideway formed therein, feed-lift mechanism including a pair of feed-lift rock-shafts, rock-arms carried by said feed-lift rock-shafts, slide-blocks pivoted to the ends of said rock-arms and entering the slide-ways formed in the legs of said feed-bar, feed-advance mechanism including a feed-advance rock-shaft, a feed-advance rock-arm, and a link connecting said feed-advance rock-arm to said feed-bar.

11. A work-feeding mechanism for sewing machines having a work-support and a circularly moving loop-taker beneath said work-support, comprising a feed-dog, a feed-bar disposed between said loop-taker and work-support and having a pair of legs arranged to straddle said loop-taker, an actuating shaft, feed-lift mechanism including a pair of feed-lift rock-shafts, rock-arms carried by said feed-lift rock-shafts and operatively connected to the legs of said feed-bar, operative connections between one of said feed-lift rock-shafts and said actuating shaft, means connecting the other of said feed-lift rock-shafts to said first feed-lift rock-shaft, feed-advance mechanism including a feed-advance rock-shaft, and connections between said feed-advance rock-shaft and one of said feed-bar legs, said last named connections being located below the level of the feed-lift rock-shafts.

12. A work feeding mechanism for sewing machines having a work support, comprising a feed dog, an actuating member, feed-dog advance and return mechanism including a rock-shaft operatively connected to said actuating member, feed-dog lift mechanism including a pair of feed-lift rock shafts, operative connections between one of said feed-lift rock shafts and said actuating member, and connections for driving the other of said feed-lift rock-shafts from said first feed-lift rock-shaft.

ARTHUR N. HALE.
